Michael Kilgore

UNITED STATES PATENT OFFICE.

ALBION F. WIXSON, OF MINNEAPOLIS, MINNESOTA.

WINDOW WEIGHT.

Application filed January 4, 1923. Serial No. 610,589.

To all whom it may concern:

Be it known that I, ALBION F. WIXSON, a citizen of the United States, residing at Minneapolis, in the county of Hennepin and State of Minnesota, have invented certain new and useful Improvements in Window Weights, and I do hereby declare the following to be a full, clear, and exact description of the invention, such as will enable others skilled in the art to which it appertains to make and use the same.

My invention relates to window weights and has for its object to provide a weight capable of being readily broken into a plurality of sections of predetermined weight. As a salient feature of this invention, I so construct the weight that the separated sections at the breaking line will have ends prepared to receive coupling devices. This feature permits all of the sections of a weight to be utilized, either individually or re-coupled together in any desired order to make up a sectional weight of substantially any desired heaviness. The weight may have any suitable form in cross-section and it may consist of two or more sections or portions capable of being readily broken apart.

To meet the demands of the trade, it has, as is well known, hitherto been considered necessary and it has been the common practice to make window weights in a very large number of different sizes, requiring a pattern for each size. It is not an uncommon thing for a dealer to carry as much as from thirty to forty different sizes of window weights, and as some of these sizes are always running out ahead of others, the dealer finds it necessary frequently to give small orders to fill in with the depleted sizes.

In some cases, it has already been the practice to provide a window weight with a small end section capable of being broken off to reduce the size of the weight, but the broken-off portion has necessarily been treated as waste or used for scrap because no provision has hitherto been made for coupling together or individually using as a weight any of the broken-off sections.

My invention practically revolutionizes the scheme of making, carrying in stock and using window weights and makes it possible for a dealer to readily meet all of the demands for the various different window weights when carrying in stock only two or

three different sizes of my improved window weights. For example, the three sizes carried might be as follows: 1. A window weight made up of three sections capable of being readily broken apart and the sections thereof in pounds representing 12—14—14. 2. A second or similar window weight in which the sections in pounds represent 6—8—10; and 3, a third weight in which the sections in pounds represent 5—7—9. Three such window weights, capable of being broken into sections such as indicated and reassembled in any desired order or used separately, will afford means for producing substantially all of the different sizes of window weights that will be required by the trade. In fact, a single three-section weight such as noted, will give a considerable range of variation in weight.

In the accompanying drawings, which illustrate the invention, like characters indicate like parts throughout the several views.

Referring to the drawings:

Fig. 1 is an elevation with some parts sectioned, showing such a window weight designed with a rectangular cross-section; and

Fig. 2 is a perspective showing a portion of one of the window weight sections and particularly indicating the line on which it is broken and the condition of that end of the weight section.

The weight illustrated is made up of three sections *a*, *b* and *c* which are adapted to be readily broken apart on definite lines by casting V-shaped channels 3 at the places 90 where the separation of the sections should be made. The upper and lower ends of the complete weight are also preferably beveled at 4.

Window weights are usually hung on the 95 lower ends of cords or chains, and to adapt such to be inserted into the ends of the weight, the latter is formed at its ends with axial passages 5 that lead to the central portions of diametric or transverse passages 6. 100 To give to the broken ends of the weight sections the same construction as is provided at the ends of the main weight, axial holes 7 are extended longitudinally of the weight from diametric or transverse passages 8, 105 which latter are located on opposite sides of the breaking lines afforded by the channels 3.

The passages 5—6 and 7—8 may be readily formed, in the process of casting the weight, 110

by the use of suitable cores. With the end construction described, a cord, cable or chain may be threaded through the axial passages 5 and 7 and may be secured by knots, cotter pins or other suitable devices seated in the transverse passages 6 and 8. Here it is important to note that the passages 6 are of much greater cross-section than the passages 5 and the passages 8 are of 10 much greater cross-section than the passages 7. The passages 7 assist in making it an easy matter to break apart the weight sections on well defined lines, but, of course, the weights at the breaking lines are strong enough to prevent any accidental breaking apart of the sections.

From the foregoing, it must be evident that there is absolutely no waste of weight sections and that each weight section may be 20 used individually as a weight or that any desired number of sections may be coupled together to produce a composite weight of any desired size. Several separated or individual weight sections may be coupled together in various different ways, as, for instance, by passing cords through the aligned passages 7 of two weight sections and knotting the ends thereof within the transverse passages 8; or, if the short chain sections 30 were used, cotter pins could be applied through the chain links within transverse passages 8.

What I claim is:

1. A window weight made up of a plurality of sections and having a weakened 35 breaking line between weight sections, and formed in the vicinity of said breaking line with cavities that afford in the ends of severed sections means for the application of coupling or supporting devices.

2. A window weight formed with at least three sections located between two weakened breaking lines and formed with axial 40 passages extended through the said weakened breaking lines and terminating in transverse passages opening at the side of the weight on opposite sides of the breaking lines and thereby affording on the broken ends of severed weight sections means for the application of suspending or coupling 45 cables or the like.

3. The structure defined in claim 1 in which said weight is also formed at the extremities of end sections with axial 50 passages terminating in transverse passages 55 opening at the side of the weight.

4. The structure defined in claim 2 in which said weight is also formed at the extremities of end sections with axial 55 passages terminating in transverse passages 60 opening at the side of the weight.

In testimony whereof I affix my signature.

ALBION F. WIXSON.
